UNITED STATES PATENT OFFICE.

CHARLES M. KIMBLEY, OF OWENSBORO, KENTUCKY.

DITCHING AND GRADING MACHINE.

1,327,047.

Specification of Letters Patent.

Patented Jan. 6, 1920.

Application filed July 17, 1918. Serial No. 245,359.

To all whom it may concern:

Be it known that I, CHARLES M. KIMBLEY, a citizen of the United States, residing at Owensboro, in the county of Daviess and 5 State of Kentucky, have invented certain new and useful Improvements in Ditching and Grading Machines, of which the following is a specification.

This invention relates to ditching and 10 grading machines.

The object of the invention is to provide a machine of this character which is simple and strong in construction, and is thorough and effective for both ditching and grad- 15 ing.

Another object of the invention is to provide a collapsible machine of this character so constructed that when not in use it may be folded compactly to occupy a minimum 20 amount of space for storing or shipping and in which the parts remain so connected that they cannot become lost when the machine is not in use.

With the foregoing and other objects in 25 view, which will appear as the description proceeds, the invention resides in the combination and arrangement of parts, and in the details of construction hereinafter described and claimed, it being understood 30 that changes in the precise embodiment of the invention herein disclosed may be made within the scope of what is claimed with- out departing from the spirit of the invention.

35 In the accompanying drawings:—

Figure 1 represents a top plan view partly in section of a machine constructed in accordance with this invention, parts being broken out for convenience in illustration.

40 Fig. 2 is a longitudinal central section thereof showing the cutting blade or scraper in operative position ready for use, and

Fig. 3 is a detail vertical section showing the scraping blade in raised inoperative 45 position.

In the embodiment illustrated, the machine constituting this invention comprises a plate 1 of heavy metal with a scraping or cutting blade 2 bolted to its lower edge, 50 said blade being shown inclined forwardly. Secured to the rear face of plate 1 is an angle iron 3, one flange of which extends laterally from said plate and is apertured to provide bearings for certain parts pres- 55 ently to be described. The upper end of plate 1 has a lateral and rearwardly ex-

tending flange 4, which is also apertured as shown at 5, some of the apertures there- in being designed to register with some of those in the flange of the angle iron 3 60 to form bearings for certain parts of the machine to be hereinafter described.

A tongue 6 carries at its front end the clevis 7 and has its rear end extended beyond plate 1 and curved downwardly and for- 65 wardly as shown at 8 with its terminal ex- tended under the horizontal flange of the angle bar 3 and secured thereto by a pintle 9 extending through apertures in said flange and tongue end. This pintle 9 also extends 70 through the tongue and through one of the apertures 5 in the flange 4 of plate 1 and is provided with a head 10 to facilitate the in- sertion and removal of the pintle 9.

A seat 11 is also carried by the curved 75 portion of the tongue and is mounted on a bar 11' bolted to said tongue as is shown clearly in Fig. 2 and on which the operator or driver of the machine is designed to ride.

A bracket 12 extends rearwardly and laterally from the curved portion 8 of the tongue and is apertured for a purpose pres- 80 ently to be described. An inverted U- shaped brace member 13 has one of its 85 legs 13' inserted through one of the apertures 6' which are formed in the tongue 6 and the other leg 13'' is removably en- gaged with one of the apertures 5 in the flange 4 of plate 1 as is shown clearly in 90 Fig. 1 and by means of which the tongue is held against lateral movement.

Supporting wheels 14 are mounted in the rear ends of curved bars 15, the front ends of which carry bearings 16 through 95 which extend axles or pintles 17 mounted in the apertures of flanges 3 and 4 which form bearings for said pintles. These bars 15 have extending upwardly therefrom at a point spaced from their connection with plate 1, studs 15' which are designed to detachably engage apertures in the hori- 100 zontal flange of an angle bar 18 which con- nects the bars 15 to hold them against lateral movement. This angle bar or iron 105 18 has its upstanding flange 19 provided with a plurality of longitudinally spaced apertures 20 which are designed to receive any implements which it may be desired to attach thereto.

110 A pintle 21 depends from bar 18 prefer- ably midway the length thereof and is de-

signed to extend through an aperture in the bracket 12 to assist in holding the tongue against lateral movement as well as to form a support for the bar 18.

5 *Mounted in apertures in the flanges 3 and 4 near the ends of plate 1 are upstanding shafts 22 which carry supporting wheels 23 at their lower ends, and at their upper ends have connected therewith levers 24 fulcrumed at 25 to standards 26 rising from the flange 4 of plate 1. These standards 26 carry sector-shaped racks 27 with which are engaged spring pressed dogs as 28 so that the levers may be locked in adjusted position. 10 These levers are designed for raising and lowering standards 22 relative to plate 1 so as to elevate or lower the cutting blade 2 to adapt it for use or not as may be desired, it being obvious that when the machine 15 is to be transported, this blade must be raised to prevent its cutting into the earth over which the machine passes.

The front end of tongue 6 is supported by a wheel 29 carried by an upright axle 30 25 which is mounted in a clevis 7, cotter pins 31 being shown passed through said shaft above and below the tongue. This clevis 7 is designed for attachment to the motive power of the machine, which may be a traction engine or it may be horse drawn by connecting double or swingletrees thereto.

When the machine is to be used for scraping or digging the parts are positioned as shown in Figs. 1 and 2, and the drawing of 35 the machine forward will cause the blade 2 to cut into the surface of the ground over which it passes, and cut out the earth therefrom or to elevate earth already loosened or cut up.

40 When the machine is not in use, and it is desired to pack it to economize in space or to ship it, the connecting brace 13 is first removed and this and bar 18 are the only parts which are actually detachable from the 45 machine entirely, bar 18 preferably remaining connected.

The cross bar 18 is then lifted off the studs 15' and the bars 15 are folded inwardly against the rear face of plate 1 the tongue 6 50 having also been swung laterally to position it over the plate and the bar 18 folded flat against plate 1 in a plane above that occupied by the bars 15. The supporting wheels 23 may also be folded flat against

plate 1 and when the parts are in this position the machine will occupy a very small amount of space, being comparatively flat with the shaft 30 and the wheel 29 carried thereby, positioned at one end and the seat 11 extended toward the other end. When 60 so collapsed this machine may be stored or packed as desired, and when it is desired to set it up for use again, this may be accomplished with very little effort and the consumption of a small amount of time. 65

The foregoing description and the drawings have reference to what may be considered the preferred or approved form of my invention. It is to be understood that I may make such changes in construction and 70 arrangement and combination of parts, materials, dimensions, etc., as may prove expedient and fall within the scope of the claimed invention.

Having thus fully described my invention, 75 what I claim as new and desire to secure by Letters Patent, is:—

In a machine of the class described, a substantially rectangular structure composed of an upstanding front plate extending transversely across the machine and having a scraper on its lower edge, longitudinally edgewise curved bars pivotally connected at one end with the ends of said plate and extending rearwardly therefrom and disposed 80 edgewise, wheels carried by the free ends of said bars, upstanding studs carried by the upper edges of said bars intermediately of their ends, an angle bar having apertures at its ends in one of its flanges said apertures 85 being engaged with said studs, the upper flange having apertures for the attachment of implements, a tongue pivoted intermediate its ends to the upper portion of said plate with its rear end curved downwardly 90 and forwardly and connected at its terminal with the lower portion of said plate, means detachably connecting said angle bar with the curved portion of said tongue, and means for vertically adjusting said scraper carrying plate and holding it in adjusted position. 95

In testimony whereof I affix my signature in presence of two witnesses.

CHARLES M. KIMBLEY.
